DESIGN.

J. L. FOLSOM.

CARPET.

No. 18,233.

Patented Apr. 3, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,233, dated April 3, 1888.

Application filed January 26, 1888. Serial No. 262,072. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of the figures A, B, C, and D and the surrounding groundwork.

Figure A has several prominent circular flower forms, which are partially covered by an 20 irregular body of shaded work, producing a watered effect. At the outer part of the figure are masses of cellular-like work with irregular projecting arms. Several small leaf forms also extend from the sides of the figure.

25 Figure B has a central portion of shaded work, producing a watered effect and having a pointed or jagged outline. From under this central portion extend at one side arms of cellular-like work. Small circular flower forms 30 with a few leaf forms are arranged around and partly underlie the central portion.

Figure C has a central portion of shaded work, producing a watered effect, having an

irregular pointed outline. From certain parts of this central portion extend or radiate arms 35 of coral-like work. A few flower and leaf forms, with a small body of cellular-like work, are also disposed around the central portion.

The figure D is composed of an irregular central portion of shaded work, producing a 40 watered effect, having a jagged or pointed outline. Several large circular flower forms with long curving leaves appear at the sides of and partly underlie the central portion. There are also several clusters of cellular-like work 45 partly underlying the central body.

These figures are arranged upon a ground-work ornamented with a watered effect.

What I claim as new, and desire to secure by Letters Patent, is— 50

1. The design for carpets, consisting of the figure A, substantially as shown.
2. The design for carpets, consisting of the figure B, substantially as shown.
3. The design for carpets, consisting of the figure C, substantially as shown.
4. The design for carpets, consisting of the figure D, substantially as shown.
5. The design for carpets, consisting of the figures A, B, C, and D and the intervening 60 groundwork, substantially as shown.

JAS. L. FOLSOM.
